UNITED STATES PATENT OFFICE.

GEORGE L. THOMAS, OF BROOKLYN, ASSIGNOR TO THE HASELL PERFECTED RAILWAY SIGNAL COMPANY, OF NEW YORK, N. Y.

ELECTRIC SIGNALING SYSTEM FOR RAILWAYS.

SPECIFICATION forming part of Letters Patent No. 556,072, dated March 10, 1896.

Application filed June 11, 1895. Serial No. 552,376. (No model.)

To all whom it may concern:

Be it known that I, GEORGE L. THOMAS, of Brooklyn, in the county of Kings and State of New York, have invented a new and useful Improvement in Electric Signaling Systems for Railways, of which the following is a specification.

My invention relates to an improvement in electric signaling systems for railways, with the object in view of providing against accident in tunnels, on bridges, or at any other special portion of a railway-line, either where the line is guarded throughout its length by a signal system or where there is no such system.

My invention is more particularly adapted to use in connection with a single-track railway along which trains pass from time to time in opposite directions.

The accompanying drawings represent a portion of the track with signals electrically interconnected through the rails of the track for signaling trains approaching in either of two opposite directions.

For purposes of explanation I will assume that the track intermediate of the two signals and denoted by A passes through a tunnel or over a bridge or some particular portion of the line which it is desirable to specially guard. Another portion of the track, denoted by A', has its rails insulated from the rails of the portion A, and a third section of the track, denoted by A'', also has its rails insulated from the rails of the section A. At the beginning of the section A which is to be guarded, assuming the train to be going from the left to the right, there is located a signal—in the present instance a semaphore - blade B—which when standing horizontally denotes

“danger” and when dropped into a downwardly-inclined position denotes “safety,” as is usual. At the opposite end of the section A, and for the purpose of signaling a train going from the right toward the left, there is a corresponding signal B'. Caution-signals C and C' are located at a distance from the signals B and B' to the left and to the right, respectively, sufficiently far away from the signals B and B' to enable a train to slow

down and be brought under perfect control before reaching the signals B B'.

The signal B is assumed to be under the control of an electromagnet D, the armature of which, when the magnet D is energized, will set in operation a suitable motor for throwing the signal B to “safety.” A motor suitable for this purpose is shown, described and claimed in my pending application, Serial No. 547,119, filed April 25, 1895, and is shown diagrammatically at E, as it forms no part of my present invention, excepting so far as it serves as one convenient means for practically operating the system herein described. In a similar manner the electromagnet D' through the motor shown diagrammatically at E' controls the movement of the signal B'.

The signals C and C' are controlled by electromagnets F and F' through similar or other suitable motors. (Shown diagrammatically at G and G'.) The electromagnet F is energized by the movement of the signal B from “danger” to “safety” positions by the closing of contact-pieces f f', the former connected by a wire f² with one pole of the electromagnet F, and the other through a battery f³ and wire f⁴ with ground. The opposite pole of the battery F is also connected with ground through the wire f⁵. In like manner the electromagnet F' is energized by the movement of the signal B' from “danger” to “safety” positions by the closing of the contact-pieces g g', the former connected with one pole of the electromagnet F' by a wire g² and the latter connected through a battery g³ and wire g⁴ with ground. The opposite pole of the electromagnet F' is also connected with ground through a wire g⁵.

A wire d leads from one pole of the electromagnet D to a battery d', from the opposite pole of which a wire d² leads to an armature h of a relay H. A wire d³ leads from the opposite pole of the electromagnet D to a contact-piece d⁴, with which the armature h of the relay H rests in electric contact when it is drawn toward the relay H by the energizing of the same. In a similar manner the poles of the electromagnet D' are connected by wires e and e', one of them passing through a battery e² with the armature h' of a relay H' and with a contact-piece e³ with which the armature h' comes into electric contact when the relay H' is energized.

The rails a a' of the track-section A' are

electrically connected to the left of the position of the cautionary signal C by a wire i , including a battery I. The rail a is also connected at or near its end adjacent to the track-section A by a wire k with one pole of a relay K, the opposite pole of said relay being connected by a wire k' with the rail a' at or near its end adjacent to the track-section A, thus completing a normally-closed electric circuit through the battery I, the rails $a a'$, the wires $k k'$, and the relay K, and hence holding the said relay K energized and its armature k^2 drawn toward it. In a similar manner the rails $a^2 a^3$ of the track-section A² at the right 15 of the track-section A are connected at a point to the right of the track-section A. There is therefore a normally-closed electric circuit through the battery I', rails $a^2 a^3$, wires $k^3 k^4$, and the relay K', tending to keep the relay 20 K' energized and its armature k^5 closed.

The rails a^4 and a^5 of the track-section A are connected at one end, the rail a^4 by a wire l with one pole of the relay II and by a 25 branch wire l' through a battery L with a contact-piece l^2 , with which the armature l^2 of the relay K is in electric contact when it is closed, and the rail a^5 by a wire l^3 with the armature l^2 of the relay K. The opposite end of the rail a^4 is connected by a wire l^4 with the armature l^5 of the relay K', and the 30 opposite end of the rail a^5 is connected by a wire l^5 with one pole of the relay II' by the branch wire l^6 through the battery L' with a contact-piece l^6 , with which the armature l^6 of the relay K' is in electric contact when closed. The opposite pole of the relay II is 35 connected by a wire m with a contact-piece m' , with which the armature l^2 rests in electric contact when it is open, and in a similar manner the opposite pole of the relay II' is connected by a wire m^2 with a contact-piece m^3 , with which the armature l^5 of the relay K' rests in electric contact when open.

In operation suppose a train to be approaching the track-section A from the left toward the right. As soon as it passes the point where the rails of the track-section A' are connected by the wire i through the battery I, it will cut out the relay K from the effect 45 of the battery I, de-energizing the relay K and permitting its armature k^2 to open. The opening of the armature k^2 , by its contact with the contact-piece m' , will complete the following electric circuit through the relay 50 H, provided the relay K' at the distant signal-tower is energized and its armature closed, viz: beginning with the armature l^2 in contact m' , along wire m to one pole of the relay II, from the opposite pole of said relay along 55 wire l to rail a^4 , to wire l^4 , to armature l^2 , to contact l^6 , to battery L', to wire l^6 , to wire l^5 , to rail a^5 , back to wire l^3 , to armature l^5 . This 60 will energize the relay H and close the armature h into contact with the contact-piece d^4 and complete the circuit through the electromagnet D, viz: from one pole of electro- 65

magnet D, along wire d to battery d' , to wire d^2 , to relay H, to contact d^4 , along wire d^3 to the opposite pole of the electromagnet D. The energizing of the electromagnet D will, 70 through the suitable motor, drop the danger-signal B to "safety," and in so doing will close the contact-points $f f'$, and thereby complete the circuit through the wires $f^2 f^4 f^5$, battery f^3 and electromagnet F, energizing the electromagnet F and through its suitable armature throwing the caution-signal C down to "safety." This will indicate to the engineer, 75 as he approaches the caution-signal C, that the danger-signal B beyond is set at "safety" 80 and the track-section A, as well as the section A² beyond, is "clear" for him to push on at such speed as he may see fit.

If, on the other hand, upon entering the section A' the engineer finds that the caution 85 or distance signal C does not drop to "clear," he is warned to slow down and creep cautiously up to the danger-signal B, and finally to stop at the danger-signal, unless in the meantime it shall have fallen to "safety" or 90 "clear" by the passage of the obstructing train off the track-sections A A².

Neither the caution-signal C nor the danger-signal B can be thrown to "safety" by the entrance of the train upon the section A', unless both the sections A and A² are free from trains, no matter whether they be moving in the same direction as the train coming onto the section A' or in the opposite direction, and this is true for a train upon the track-section A² will, by cutting out the battery I' from the circuit in which the relay K' is located, de-energize the relay K', and hence open the armature l^5 and so break the circuit, which, as has been above noted, must be 105 completed in order to energize the relay II to throw the signal B to "safety" or "clear." Again, if the train were on the section A it would cut out the battery L' from the relay II, and hence the relay II could not be energized. 110 In the same manner a train coming from the right toward the left would operate its caution and danger signals, provided the track-sections A and A' were both "clear;" but if a train were on either of them it would be 115 unable to get a clear signal until the trains had passed off.

What I claim is—

1. In combination, a track-section having its rails insulated from adjacent track-sections, the adjacent track-sections each having their rails in electric circuit with a relay, the one with a relay at a signal-tower at one end of the intermediate track-section and the other with a relay at a signal-tower at the 125 opposite end of the intermediate track-section, a signal-controlling electromagnet at each of said towers and electric circuits including the rails of the intermediate track-section, the armatures of the said relays and 130 a second relay at each of said towers for permitting or preventing the operation of the

signals at the towers, according to the position or positions of a train or trains on said track-sections, substantially as set forth.

2. In combination, an intermediate track-section, the rails of which are insulated from adjacent track-sections, a signal for indicating danger and safety at each end of said intermediate track-section, a distance or caution signal under the control of the movement of each of said danger and safety signals, electric circuits including electromagnets for controlling the movements of the said danger and safety signals, electric circuits

each including the rails of the intermediate track-section for making and breaking the circuits through the electromagnets and electric circuits including the rails of the adjacent track-sections for making and breaking the circuits which include the rails of the intermediate track-section, substantially as set forth.
